UNITED STATES PATENT OFFICE.

LOUIS RITTER AND JACOB RITTER, OF NEW YORK, N. Y.

BELT-BUCKLE.

SPECIFICATION forming part of Letters Patent No. 655,371, dated August 7, 1900.

Application filed June 22, 1900. Serial No. 21,153. (No model.)

To all whom it may concern:

Be it known that we, LOUIS RITTER and JACOB RITTER, citizens of the United States, residing in the city of New York, borough of 5 Manhattan, and State of New York, have invented certain new and useful Improvements in Belt-Buckles, of which the following is a specification.

Our invention relates to that class of buckles used, preferably, for ladies' belts; and the object of the invention is to provide a belt-buckle which is simple, durable, and effective and which is not liable to get out of order.

15 The invention consists of a belt-buckle which comprises two slide members constructed so that they may be slid one on the other, the face of one member being provided with a longitudinal series of teeth inclined 20 on one side and squared on their operative side and the other member being provided with opposite edge notches, a link for engaging with said teeth, said link having notched rearwardly-bent portions hung into the said 25 edge notches, so as to form a hinge-joint, and a back bar connecting said bent portions and provided with a heel extending in the same direction as the locking or loop portion of the link, so as to form a short lever, which is 30 acted on by a suitable spring tending to engage the loop end of the link with said teeth, all as will be hereinafter described in detail and then pointed out in the claims.

In the accompanying drawings, Figure 1 is 35 a front elevation of our improved belt-buckle, showing the position of the parts when in use. Fig. 2 is a front elevation of one of the slide members of the buckle, the link being omitted; and Fig. 3 is a similar view of the other 40 member. Fig. 4 is a detail perspective view of the link. Fig. 5 is an enlarged longitudinal section on line 5 5, Fig. 1; and Fig. 6 is an enlarged section on line 6 6, Fig. 1.

Similar letters of reference indicate corresponding parts.

45 Referring to the drawings, A B indicate two slide members composed of suitable plates of metal and secured in any suitable manner to the ends of the belt. The members A B 50 are curved transversely at their longitudinal intermediate portions to form ribs a b, rib b being provided with a series of teeth b', having

square shoulders all standing in one direction and inclined faces extending in the opposite direction. At the adjacent ends of the central longitudinal ribs the slide members are formed with narrow side flanges f and at the opposite ends with wider side flanges f', which practically define the width of the buckle, so as to impart a finished appearance and solidity. 55 Slide member A moves under the slide member B as its rib a slides within said rib b, and the edges of the flanges f' of slide member A are provided with directly-opposite notches c c, adapted for the connection of a 60 suitable link D, the loop-shaped front portion of which is adapted to engage with the square shoulders of the teeth b' and to freely ride over the inclined surfaces of the teeth in well-known manner. For the purpose of 65 hinging the link D the same is provided with rearwardly-bent portions d, which are notched at d', such notched portions d being hung in the notches c of slide member A. The rear ends of the portions d are connected by a 70 transverse back bar e, which is formed at its mid-length with a heel e', which extends a short distance in the same direction as the front loop of the link, so as to form a short lever. A semi-elliptic or curved spring g is 75 seated at its ends in the groove at the back of the rib a, while its humped back bears elastically against the heel e', thereby tending to force the longer front loop of the link 80 D into engagement with one of the teeth b'. 85

By constructing the link D with the short heel e and extending it in the direction of the loop of the link it is only necessary to exert a slight spring-pressure upon that side of the heel adjacent to the slide member A. Said 90 spring g by being located between the transverse back bar e and the slide member A is retained in position, and it cannot be easily dislocated, and a better action is obtained by such spring than by a spring which simply 95 engages at its extremity with a portion of the link.

Having thus described our invention, what we claim as new, and desire to secure by Letters Patent, is—

100 1. A belt-buckle, comprising two slide members, movable one on the other, one of said slide members being provided with a longitudinal series of teeth and the other with dia-

- metrically-opposite edge notches, a link having rearwardly-bent portions hung in said notches to form a hinge-joint, said bent portions being connected by a back bar provided
- 5 with a heel projecting in the same direction as the engaging front loop of the link, and a spring engaging that side of said heel which is adjacent to the link-supporting member, substantially as set forth.
- 10 2. A belt-buckle, comprising two slide members, provided with longitudinal ribs, with narrow flanges at each side of the adjacent ends of the ribs and wider flanges at the opposite ends, one of said slide members having opposite notches in its wider flanges, and the other having a series of teeth on its rib, a link having rearwardly-bent portions hung in said notches to form a hinge-joint, said

bent portions being connected by a back bar projecting in substantially the same direction as the engaging front loop of the link, and a semi-elliptic spring, the ends of which are seated in the groove at the back of the rib of the link-supporting slide member and the humped back of which bears on that side of

20 said heel which is adjacent to the link-supporting slide member, substantially as set forth.

In testimony that we claim the foregoing as our invention we have signed our names in

25 presence of two subscribing witnesses.

LOUIS RITTER.
JACOB RITTER.
